UNITED STATES PATENT OFFICE.

SIMON KLEIN, OF BROOKLYN, NEW YORK.

FAUCET.

1,196,786.

Specification of Letters Patent.

Patented Sept. 5, 1916.

Application filed October 26, 1915. Serial No. 57,905.

To all whom it may concern:

Be it known that I, SIMON KLEIN, citizen of the United States of America, residing at Brooklyn, in the county of Kings and State of New York, have invented certain new and useful Improvements in Faucets, of which the following is a specification.

The object of the present invention is to provide a faucet, such as used on beer kegs or the like, with means whereby, when the contents of a receptacle discharged through the said faucet assume a certain weight, the faucet will be automatically closed.

To accomplish my object, the faucet is provided with a valve, a controlling means therefor and a weighing mechanism, which serves for the suspension of a receptacle and which will actuate said controlling means so as to close the valve as soon as the desired weight or quantity is dispensed.

In the drawing, which forms part of this specification and in which similar reference characters denote corresponding parts, Figure 1 shows a side elevation of my faucet fixed to a barrel; Fig. 2 is an enlarged top plan view of the faucet; Fig. 3 is an enlarged longitudinal section of the faucet and Fig. 4 is a cross section on line 4—4 of Fig. 2.

The faucet consists of the tubular piece *a* formed at its outer end with a casing *a'* containing the cock *b* which is hollow and has at its bottom a tubular threaded extension *b'* (Fig. 3). The cock is tightened in well known manner by a spring washer *c* and a nut *d* working on the outer face of the extension *b'*. Screwed into the interior of the extension is a mouthpiece *e* which at its inner end is formed with a seat *e'* for a valve *f* loosely arranged in the hollow of the cock *b*. Extending downwardly from the piece *a* is a bifurcated arm *g* to which is fulcrumed a lever *h*. The forward end of said lever carries a conical pin *h'* which during the normal position of the lever *h* extends through the said mouthpiece *e* into the hollow of the cock and holds the valve *f* lifted from its seat, so that when the cock is opened the liquid may freely flow out through the said mouthpiece. The opposite

end of the lever *h* loosely engages a slot or opening *i'* of a weight *i* which at *i'* is pivotally suspended from a frame *j*. The frame *j* is pivotally suspended from the casing *a'* of the cock *b* by means of pins *k*, *k* borne

in ears *a'* projecting upwardly from the longitudinal members of the frame *j*. Movable supported on the frame is a U-shaped piece *m* which at its rear is formed with hook-shaped members *m'* slidably engaging around the longitudinal members of the frame *j* and at its forward end is provided with a cross piece *m'*. The latter is provided with a threaded eye *m'* in which works a screw *o* which with a cylindrical unthreaded portion *o'* is rotatively borne in the cross piece *j'* of the frame *j*. The cylindrical portion *o'* has a circumferential groove *o''* for the engagement of a set screw *p* working in the cross piece *j'* of the frame *j* whereby the screw *o* may be secured in its adjusted position. In the upper edges of the longitudinal members of the frame *m* are notches *m''* to receive the handle *C'* of a can *C* or the like (Fig. 3). The lever *h* is held in its normal position, *i.e.* in the valve opening position by the weight *i* resting on the rear end thereof. The slot or opening *i'* in the weight *i* is deep enough to permit some play to the lever *h*. The frame *j* is supported in normal or horizontal position by stops *a* projecting from the piece *a*.

The mode of operation is as follows: When the can suspended from the piece *m* is filled with the desired quantity of the liquid overbalancing the weight *i*, the forward end of the frame *j* will tilt, lifting the weight and thereby releasing the lever *h*. The forward end of the lever *h* owing to the gravity of the valve *f* will swing downwardly, as shown by dotted lines in Fig. 3, withdrawing the pin *h'* and permitting the valve *f* to fall on to its seat and to close the mouthpiece *e*. As the cans or receptacles may differ in weight they may be suspended farther from or nearer to the fulcrum of the frame *j* so as to avoid a variation in the quantity dispensed. By adjusting the frame *m* by means of the adjusting screw *o* the quantity to be dispensed can be varied.

As the structure can be variously modified without departing from the principle of my invention, I do not limit myself to the details described and shown.

What I claim and desire to secure by Letters Patent is:

1. A measuring faucet, comprising a hollow cock having a valve seat, a valve, a gravity operated valve lifting member pivotally suspended from said cock, a weighted receptacle suspension member pivotally sus-

5 pended from said cock and loosely engaging with its weighted end said first named member, so as to normally cause the latter to lift said valve and to release the same on being overbalanced and tilted by the discharge filling the receptacle.

- 10 2. A measuring faucet, comprising a hollow cock having a valve seat, a valve, a gravity operated valve lifting member pivotally suspended from said cock, a weighted member pivotally suspended from said cock, a receptacle suspension member adjustably supported on said weighted member, the latter engaging said valve lifting member so as to normally cause the latter to lift said valve and to release the same on being overbalanced and tilted by the discharge filling the receptacle.
- 15 3. A measuring faucet, comprising a hol-

low cock, having a valve seat, a valve, a gravity operated valve lifting member pivotally suspended from said cock, a frame pivotally suspended from said cock and carrying a weight at one end, a receptacle suspension member adjustably supported on the other end of said frame, the weight of said frame loosely engaging said valve lifting member so as to normally cause the latter to lift said valve, and to release the same on being overbalanced and tilted by the discharge filling the receptacle.

20 In testimony whereof I affix my signature in presence of two witnesses.

SIMON KLEIN.
